Inventor
Joseph Haering,

By A. Munro Talbert

Attorney

UNITED STATES PATENT OFFICE.

JOSEPH HAERING, OF LOUISVILLE, KENTUCKY.

COW-TAIL HOLDER.

Application filed December 2, 1921. Serial No. 519,454.

To all whom it may concern:

Be it known that JOSEPH HAERING, a citizen of the United States of America, residing at Louisville, in the county of Jefferson and State of Kentucky, has invented new and useful Improvements in Cow-Tail Holders, of which the following is a specification.

The object of the invention is to provide simple and efficient means for holding the tail of a cow during the time when she is housed in cool weather, so that the tail may be maintained at a sufficient distance from the floor to be kept free of the filth thereon. 10 Further the object is to secure the tail in such a position that anything thereon will be precluded from falling or dropping into the milk. Further, the purpose of the invention is to save the time of the milker, 15 since the supporting of the tail as provided by the invention, will make it unnecessary to wash the cow before milking. With these objects in view the invention consists in a construction and combination of parts of 20 which a preferred embodiment is shown in the accompanying drawings, wherein:—

Figure 1 is a view of a holder embodying the invention arranged in the operative position.

Figure 2 is a side view of the holder clamp. 30 Figure 3 is an edge view of the same. The holder consists of a clamp or strap 10 of flexible material adapted to be rolled or wrapped around the tail of the cow near its extremity and provided with an eye 11 for engagement with a stud 12, and engaged with the stud is a cotter pin 13 to hold the eye in engagement therewith. As shown in the drawing the strap may be provided with 35 a plurality of eyes 11, either of which may be engaged with the stud, so as to provide for adjustment to suit the size or thickness of the tail which is engaged thereby.

The strap or clamp is also preferably anchored to a fixed object as by means of a flexible cord 14 adapted to be engaged with an eye 15 in the end of the strap opposite to the eyes 11, and in the construction illustrated the anchoring means is indicated 40 as a staple 16 secured to some fixed object

such as a wall shown at 17. In order that the efforts of the cow to move the tail may not meet with a fixed obstruction or resistance which might tend to cause restiveness of the animal it is preferable to provide the anchoring cord 14 with a yielding element consisting for example of a spring 18 serving to break the jar and yield to a certain extent to the movements of the tail.

Moreover in order that the disengagement 60 of the clamp or strap from the tail may be effected without manipulation on the part of the operator a releasing cord 19 connected with the anchoring means is attached to the cotter pin 13 as shown in Figure 1. 65 When the milking operation has been completed and the cow is permitted to leave the position occupied during the milking operation, the strain upon the anchoring cord 14 will stretch the spring 18 and thereby 70 tighten the releasing cord 19 which will disengage the cotter pin from the stud 12 and thereby release the clamp.

In order to preclude the possibility of the tail becoming entangled with the cords 75 14 and 19, there is provided a tubular member 20 through which the cords are inserted prior to attaching the clamp or strap 10, the lower end of the tubular member resting 80 against the strap.

Having described the invention, what is claimed as new and useful is:—

A cow tail holding device consisting of a clasp having a flexible member provided with a stud, and a plurality of eyes for selective engagement with the stud, a key detachably engaged with the stud for holding an eye in engagement therewith, anchoring and releasing cords for connection with an overhead support and also having connection respectively with the flexible member of the clasp and said key, the anchoring cord including an elastically extensible member, and a protective sheath embracing the anchoring and releasing cords adjacent to the clasp for preventing the entangling 90 of the cow tail therewith.

In testimony whereof he affixes his signature.

JOSEPH HAERING.
